DESIGN FOR A SERVING PLATTER OR SIMILAR ARTICLE

Sol Forman, New York, N. Y.

Application May 15, 1939, Serial No. 84,994

Term of patent 3½ years

To all whom it may concern:

Be it known that Sol Forman, a citizen of the United States and resident of New York city, in the county of New York and State of New York, has invented a new, original, and ornamental Design for a Serving Platter or Similar Article, of which the following is a specification, reference being had to the accompanying drawing, forming part thereof, and in which,

Fig. 1 is a top plan view of a serving platter or similar article, embodying my new design;

Fig. 2 is a side elevational view thereof, with parts in cross-section; and

Fig. 3 is a bottom plan view thereof.

I claim:

The ornamental design for a serving platter or similar article, substantially as shown.

SOL FORMAN.
